Primary Examiner — Dana K Weiland*Assistant Examiner* — Messina L Smith(74) *Attorney, Agent, or Firm* — Studebaker & Brackett
PC(57) **CLAIM**

The ornamental design for a griddle, as shown and described.

DESCRIPTION

FIG. 1 is a front, top, and right-side perspective view of a griddle showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof; and,

FIG. 8 is a rear, top, and left-side perspective view thereof. The broken lines illustrate portions of the griddle and form no part of the claimed design.

1 Claim, 8 Drawing Sheets(56)
